UNITED STATES PATENT OFFICE

1,998,678

SIGNAL LIGHT

Carl H. Larson, Elkhart, Ind., assignor to The
Adlake Company, a corporation of Illinois

Application August 10, 1929, Serial No. 384,822

3 Claims. (Cl. 177—329)

This invention relates to signal lights and the principal object of the invention is the provision of new and improved means for adjusting the lighting mechanism.

5 Another object of the invention is the provision of a new and improved signal lamp having novel mechanism for adjusting a lens and a source of light simultaneously.

A further object of the invention is the provision of a signal lamp having its lens and source of light so mounted that they may be adjusted simultaneously, independently of the lamp casing, together with novel means for adjusting the same, which is accessible from a point without 10 the lamp casing.

Other and further objects and advantages of the invention will appear from the following description taken in connection with the accompanying drawings, in which

20 Fig. 1 is a plan view of a signal device disclosing the invention and with the supporting post in section;

Fig. 2 is a front elevation thereof, with parts in section;

25 Fig. 3 is a front elevation of one of the lamps; Fig. 4 is a section on line 4—4 of Fig. 3;

Fig. 5 is a front elevation of the base member with the closure removed, with parts broken away;

30 Fig. 6 is a section on line 6—6 of Fig. 3; Fig. 7 is a section on line 7—7 of Fig. 5; and Fig. 8 is a section on line 8—8 of Fig. 5.

In the use of signal lamps or lights at points where highways cross the railway tracks, it is 35 common practice to employ two lamps at the side of the highway adjacent the track, and to provide means for alternately energizing the sources of light in the lamps for simulating the swinging of a lantern for indicating the approach of trains 40 crossing the highway.

The present invention is shown in connection with a signal system of this type, although it is understood that it may be used in other types of signals and in other relations.

45 Referring now to the drawings, the reference character 10 designates a signal lamp support on which is mounted the usual signs 11 indicating a railway crossing. Attached to the support 10 in any suitable manner as by the plate 12 and clamp 13 is a cross or supporting arm 14 by which the signal lamps 15 are supported. The lamps are secured to the cross arms 14 in any suitable manner.

50 As shown, each lamp 15 is provided with a screw-threaded socket 16 in which one end of a

screw-threaded supporting pipe 17 engages, the other end being screw-threaded in a T-pipe connector 18, the sleeve portion 19 of which is adapted to be threaded on to one of the ends of the arms 14 in the usual manner. By means of this arrangement the lamp may be adjusted in a horizontal plane and secured in adjusted positions on the pipe 17 by the set screws 21 and 22. The lamp is prevented from swinging in a vertical plane by the set screw 23. The outer end of each of the sleeve portions 19 may be provided with a screw-threaded plug 24 for preventing the entrance of dust, dirt and moisture into the sleeve member and from thence into the lamp casing. By the employment of a T-pipe connector the lamps may be attached to either end of the supporting arm 14 as may be desired and the exposed end closed by the plug 24.

55 The lamps 15 are identical, so only one need be described. Each lamp comprises a casing 25 composed of the hollow base member 26 and the closure member 27. The base member 26 is provided at its upper end with the socket 16 by which it is attached to the supporting rod or post 17 and with a hinge member 28 to which is pivotally attached a corresponding hinge member 29 on the closure member 27 for forming the hinge 31. The closure member 27 comprises a cylindrical member 32 having an inturned flange 33 against which a flange 34 on a lens 35 is adapted to seat. The flange 34 of the lens is held against its seat by suitable clips 36. The lens 35 is of the type that directs the rays of light forwardly and laterally. Since the specific features of the lens constitute no part of the present invention it is not thought necessary to further illustrate or describe the same.

60 A suitable reflector and source of light are provided for the lamp. In the form of construction selected to illustrate one embodiment 40 of the invention, the source of light is electrically energized and the reflector and electric bulb are so connected as to be adjusted together simultaneously. As shown, the reflector 37 is held in position within the lamp casing by a ring 45 member 38. The ring member is provided with inwardly extending fingers 39 which are adapted to engage the rear surface of the reflector 37 for limiting its outward movement. The front edge of the ring member 38 is provided with radially extending lugs 41 to which clips 42 are secured (see Fig. 5). The clips 42 extend radially inward and engage the front edge of the reflector 37 for securing the same in position against the fingers 39. A set screw 40, extending radially 55

inward from the ring member 38, is adapted to engage a suitable recess in the lens 37 for preventing its rotation.

The ring member 38 is also provided with a 5 depending lug 43 to which is attached the lower end of a lamp socket support 44. The lamp socket support 44 is insulated from the ring member 38 in the usual manner (see Fig. 8) and is secured thereto by bolts 45 and 46. The bolt 10 46 is insulated from the ring member 38 and the support 44 in a manner well known in the art. The bolts 45, 46, constitute binding posts for the electric wires 47, 48, of the lead 50. The bolt 45 is insulated from the ring member but is in 15 electrical connection with the support 44, whereby the support will constitute a portion of the electric circuit.

The upper end of the supporting member 44 is provided with an opening in which the lamp socket 49 is slidably mounted, and is frictionally held in adjusted position therein. An electric 20 lamp or light bulb 50 is adapted to be secured in said socket in the usual manner.

The axis of the socket 49 is arranged in the 25 axis of the lens so that in focusing the light it is only necessary to slide the socket 49 inward and outward through the opening in the support 44. The outer end of the socket 49 is provided with one or more binding posts depending on 30 whether the bulb is a single or double contact type. As shown, the bulb is single contact and the wire or lead 48 is attached to the single binding post 51 in the usual manner. The support 44 may, if desired, be provided with apertures 35 through which clips 52 may extend for engaging the wire 48 for holding the same in close proximity to the support 44.

Considerable difficulty has been experienced in 40 maintaining the interior of signal lights or lamps free of dust, dirt, and other foreign matter. In adjusting the lens or bulb in the usual manner the hand of the operator is likely to come in contact with the lens or bulb and befoul the surfaces of one or the other, or both of them, thereby detracting from the brilliancy of the reflected rays as well as permitting dust, dirt, rain, snow, 45 and the like, to enter the casing while the same is open, and be deposited on the lens.

Furthermore, when the adjusting mechanism 50 is within the lamp casing considerable difficulty is experienced in adjusting the bulb, especially where the lens is mounted on the closure, because after each adjustment the closure must be closed to determine whether the adjustment is 55 sufficient or is too much. It thus takes repeated efforts and considerable time to secure the proper adjustment of the bulb relative to the reflector.

The present invention seeks to avoid these difficulties by obviating the necessity for opening 60 the casing when it is desired to adjust the direction in which the reflected rays are projected.

As shown, the base member 26 is provided with 65 inwardly extending lugs 53, 54 (see Fig. 6), to which the ring member 38 is adapted to be pivoted, as by means of the pivots 55 and 56, which extend through the lugs 53, 54, respectively, and are screw-threaded into laterally extending lugs 57, 58, on the ring member 38 to form the hinges 59 and 61 for said ring member.

The hinge members 59, 61, are arranged at 70 each side of the ring member 38 so that said member may swing about a horizontal axis for directing the rays of light from the lamp upwardly or downwardly, as desired.

75 Means are provided for holding the ring mem-

ber 38 in adjusted position. In the form of construction selected to illustrate one embodiment of the invention, the ring member 38 is provided with a radially extending lug 62 adjacent its lower edge (see Fig. 7). A bolt 63, projecting through the base member 26, has its inner end extending through an enlarged opening in the lug 62, and is provided with a nut 64. This nut is prevented from turning by suitable projections 65 on the lug 62. The lug 62 is held in engagement with the nut 64 by a spring 66. The outer end of the bolt 63 may be provided with the usual slot or kerf, whereby the bolt may be turned by a screw driver for adjusting the lug 62 along the bolt 63 for tilting the reflector and lamp bulb. 15

The base member 26 may, if desired, be provided with sight members 67 and 68 (see Fig. 6), which have their line of sight diverging forwardly from the lamp forming an angle substantially bisected by the vertical plane of the axis of the 20 reflector, whereby the field of illumination of said lamp may be determined by said sight devices without energizing said source of light. By means of this arrangement, the proper position of the casing when the lamp is installed or adjusted is 25 determined. A side member 67 is provided with a groove on its outer surface as indicated at the dotted line in Fig. 6, as the side member 68 is provided with a V-shaped edge which constitutes the 30 bead in sighting along the groove in the member 67.

The closure member 25 is provided with an annular recess 69 for containing fibrous or other material 71 which is adapted to be clamped against the flange 72 of the base member 26 for 35 constituting a dust-tight and weather-proof joint between the closure and the base member. Any suitable means may be provided for clamping the closure member 25 to the base member 26. As shown, the closure member 25 has pivoted thereto 40 a link 73 to which an eccentric latch 74 is pivotally connected. The latch 74 is adapted to have its nose 75 engage a lug 76 on the base member 26 45 when the parts are in clamping position. The free end of the latch is provided with a slot 77, through which a staple 78, on the base member, is adapted to extend when the parts are in the 50 position shown in Fig. 4. The latch may be locked in operative position by a padlock, or the like, engaging the staple 78 in the usual manner.

The sides of the casing may be provided with 55 lens or bulls eyes 79, 81, for permitting rays of light to pass laterally from the casing to indicate signals to an observer opposite the lamps. The casing may also be provided on its lower side with a 60 ventilating opening 80, having wire mesh 99 extending across the same for preventing the entrance of dirt and other foreign matter.

If desired, the closure may be provided with a visor 82 extending about the upper and side portions of the lens, as is usual in such constructions. 65

In adjusting the lamps their horizontal adjustment is obtained by loosening the set-screw 21 and turning the casing about the pipe 17 to the desired position, the sight members 68 and 67 being employed for indicating the proper position to which the lamp should be turned. If it is desired to elevate or lower the beam of light the ring member 38 is rotated about its horizontal axis 70 by turning the screw 63 in the proper direction. It will thus be seen that the rays of light projected from the casing may be adjusted either laterally or vertically without the necessity of opening the lamp casing. 75

I claim as my invention:

1. In a signal light, a casing comprising a shallow base portion, a deep closure for said base portion, a transparency in the front of said closure, a reflector, a combined bulb and reflector support, horizontally arranged pivots adjacent to the forward edge of said base portion for adjustably mounting said support on said base portion with the forward edge of said reflector adjacent to the plane of the forward edge of said base portion, said support comprising an arm extending upwardly and forwardly of the forward edge of said base portion, a light bulb supported by said arm forwardly of said base portion within said closure, and means extending from the rear of said base portion exterior thereof for adjusting said support about said pivots.
2. A signal lamp comprising a two-part casing including a shallow stationary portion opening forwardly and a deep closure portion hinged to said stationary portion and containing a transparency in its front wall, a source of light, a reflector for reflecting rays from said source of light through said transparency, a common support for said reflector and source of light, said support secured within said stationary portion and extending forwardly into said closure portion, the front edge of said reflector being supported substantially in the plane of the forward edge of said shallow stationary portion and said source of light being supported substantially forwardly of said plane, whereby access may be readily had to said support, reflector and source of light when said closure is opened.
3. In a signal lamp, a casing, a frame pivotally mounted in said casing, a reflector and a source of light mounted on said frame, means extending from said frame to the exterior of said casing at the rear thereof for adjusting said frame about a horizontal axis, a support, means for adjustably connecting said casing to said support to swing about a vertical axis and with it said reflector and source of light and a pair of sight devices on said casing, the lines of sight of said devices diverging forwardly of the lamp and forming an angle substantially bisected by the vertical plane containing the axis of said reflector, the angle between the sight devices being substantially the angle of the spread of the beam from said source of light, whereby the field of illumination of said lamp may be determined by said sight devices without energizing said source of light.

CARL H. LARSON.
